UNITED STATES PATENT OFFICE

133,182

DESIGN FOR A SOLENOID FIRING MECHANISM FOR MACHINE GUNS

John C. Koonz and La Vern Edward Quinnell,
Fort Wayne, Ind., assignors to The Magnavox
Company, Incorporated, Fort Wayne, Ind., a
corporation of Indiana

Application November 15, 1941, Serial No. 104,164

Term of patent 14 years

To all whom it may concern:

Be it known that we, John C. Koonz and La Vern Edward Quinnell, citizens of the United States, residing at Fort Wayne, in the county of Allen and State of Indiana, have invented a new, original, and ornamental Design for Solenoid Firing Mechanism for Machine Guns, of which the following is a specification, reference being had to the accompanying drawing, forming a part thereof.

In the drawing:

Fig. 1 is a perspective view of a solenoid firing

mechanism for machine guns embodying our design viewing the device from one side, and

Fig. 2 is a similar view looking at the device toward the end which is positioned adjacent to the machine gun when put to use.

We claim:

The ornamental design for a solenoid firing mechanism for machine guns, substantially as shown.

JOHN C. KOONZ.
LA VERN EDWARD QUINNELL.
